ABSTRACT OF THE DISCLOSURE

A holder for selectively storing and presenting a plurality of cartridges, such as cassette cartridges and the like. The holder includes a housing and a carrier removably associated with the housing to store cartridges in the housing in a closed arrangement of the holder and to selectively present the cartridges for facilitated removal and placement into the carrier in an open arrangement of the holder. The carrier and housing are arranged to dispose the carrier in an upwardly tilted disposition in the open arrangement and in a position effectively closing the front opening of the housing in the closed arrangement.

BACKGROUND OF THE INVENTION

Field of the invention

This invention relates to storage holders and in particular to storage holders for use with cartridges such as cassette cartridges and the like.

Description of the prior art

In storing cassette cartridges and the like, it is desirable to provide means for effectively enclosing a plurality of such cartridges in a storage arrangement while permitting facilitated handling of the cartridges when desired by selectively arranging the holder in an open arrangement. No fully satisfactory cassette holder has been developed providing the desired facilitated enclosure of the cassettes in one arrangement and facilitated presentation of the cassettes for selective use in a second arrangement.

SUMMARY OF THE INVENTION

The present invention comprehends an improved holder for selectively storing and presenting a plurality of cartridges such as cassette cartridges and the like.

More specifically, the invention comprehends the provision of such a holder having a housing provided with a front opening. A carrier is arranged to carry a plurality of cassette cartridges or the like. The carrier and housing are arranged so that the carrier may be installed in the housing with the cartridges effectively enclosed therein in a storage disposition.

The carrier is further arranged to be mounted in the housing in an open disposition wherein the cartridges are presented for facilitated removal and return by the user. In the open disposition, the carrier is automatically disposed in a forwardly upwardly inclined arrangement, facilitating the manipulation of the cartridges by the user.

The carrier is selectively manipulated to the respective open and storage dispositions by ready manipulation of the carrier relative to the housing. The housing may be provided with recess and aperture means permitting access to portions of the carrier for facilitating such manipulation of the carrier. Cooperating shoulder means on the housing and carrier provide for automatic positioning of the carrier relative to the housing in each of the open and storage dispositions facilitating the use of the holder.

The holder may be formed of molded plastic or the like and is extremely simple and economical of construction while yet providing the highly desirable features discussed above.

2

BRIEF DESCRIPTION OF THE DRAWING

Other features and advantages of the invention will be apparent from the following description taken in connection with the accompanying drawing wherein:

FIG. 1 is a front perspective view of a plurality of cartridge holders embodying the invention in stacked association and with the carriers thereof arranged in an open disposition presenting the cassette cartridges for removal and return to the holder;

FIG. 2 is a perspective view of a holder in the storage disposition;

FIG. 3 is a rear view of the stacked arrangement of holders of FIG. 1;

FIG. 4 is a fragmentary enlarged horizontal section taken substantially along the line 4—4 of FIG. 2;

FIG. 5 is a fragmentary vertical section taken substantially along the line 5—5 of FIG. 4;

FIG. 6 is a fragmentary vertical section taken substantially along the line 6—6 of FIG. 4 with the carrier in the storage disposition;

FIG. 7 is a fragmentary vertical section illustrating the mounting of the upper holder on the lower holder;

FIG. 8 is a fragmentary horizontal section taken substantially along the line 8—8 of FIG. 7;

FIG. 9 is an enlarged fragmentary vertical section of the stacked holders of FIG. 1 with the carriers in the open disposition;

FIG. 10 is a fragmentary rear elevation taken substantially along the line 10—10 of FIG. 9;

FIG. 11 is a fragmentary substantially vertical section taken substantially along the line 11—11 of FIG. 6; and

FIG. 12 is a fragmentary substantially vertical section taken substantially along the line 12—12 of FIG. 9.

DESCRIPTION OF THE PREFERRED EMBODIMENT

In the exemplary embodiment of the invention as disclosed in the drawing, a holder generally designated 10 such as for use in selectively storing and presenting for use a plurality of cartridges such as cassettes 11, is shown to include a housing 12 and a carrier 13 removably associated with the housing. Carrier 13 may be associated with housing 12 selectively in a storage disposition, as shown in FIG. 2, and in an open disposition, as shown in FIG. 1. As further shown in FIG. 1, the holders are arranged to be vertically stacked as desired.

As seen in FIGS. 4 and 6, housing 12 includes a bottom wall 14, a pair of upstanding end walls 15 and 16, a top wall 17, and a rear wall 18. Bottom wall 14, end walls 15 and 16, and top wall 17 cooperatively define a front opening 19 through which the carrier is removably installed in the space 20 within the housing. As shown in FIG. 6, bottom wall 14 may be provided with a depending outturned flange 21 and top wall 17 may be provided with an upstanding inturned flange 22. As shown in FIG. 7, flanges 21 and 22 selectively fit to effectively mount an upper holder 10' to a lower holder 10 in the stacked arrangement of FIG. 1. As shown in FIG. 9, lower flange 21 includes a front portion 23 which abuts a front portion 24 of upper flange 22 to position the stacked holders in vertically aligned association.

Carrier 13 includes bottom wall 25 and an upright edge wall 26. In the storage disposition of FIG. 6, edge wall 26 comprises the front wall of the carrier effectively closing housing opening 19. In the open disposition of the holder as shown in FIG. 9, the edge wall 26 comprises the rear wall of the carrier cooperating with bottom wall 25 to support the cassettes in the carrier. As shown in FIG. 9, the carrier is disposed in a forwardly upwardly inclined arrangement in the open disposition for facilitated re-

removal and replacement of the cassettes relative to the carrier in housing 12.

Carrier 13 further includes a plurality of upright dividers 27 extending upwardly from bottom wall 25 to a mid-portion of edge wall 26. The dividers effectively divide the space defined by bottom wall 25 and edge wall 26 of the carrier into a plurality of compartments 28 adapted to receive one each a cartridge 11.

As indicated briefly above, the holder may be inexpensively formed of molded plastic and, thus, dividers 27 may be molded integrally with the carrier walls 25 and 26. The carrier may further be provided with a pair of opposite end walls 29 and 30 which extend from bottom wall 25 substantially to the top of edge wall 26 as best seen in FIGS. 6 and 9. Housing end walls 15 and 16 may each be provided with a forwardly opening recess 31 exposing a portion of carrier end walls 29 and 30 for manual grasping of the carrier for use in moving the carrier between the storage disposition of FIG. 6 and open disposition of FIG. 9. As shown in FIGS. 1, 6 and 9, the carrier end walls 29 and 30 include forwardly projecting upper end portions 32. As best seen in FIGS. 4 and 11, end walls 29 and 30 are provided with bosses 33 which project into corresponding openings 34 in housing end walls 15 and 16 when the carrier is disposed in the storage disposition. As shown in FIG. 12, bosses 33 merely ride on the inner surface of housing end walls 15 and 16 in the dispositions of the carrier within the housing. Thus, bosses 33 and openings 34 cooperatively define means for effectively releasably holding the carrier in the storage disposition against inadvertent opening of the holder while yet permitting facilitated movement of the carrier to and from the storage disposition by the user when desired.

As indicated briefly above, the housing and carrier are provided with means for automatically positioning the holder within the housing in each of the storage and open dispositions. Thus, as seen in FIG. 5, housing bottom wall 14 may be provided with an upstanding shoulder 35 adjacent rear wall 18 for abutment by the front edge 36 of carrier bottom wall 25 when the carrier is installed in the housing in the storage disposition. In this disposition, edge wall 26 is automatically disposed flush across front opening 19 of the housing. The portion of housing space 20 rearwardly of carrier edge 36 accommodates the outwardly projecting cassettes to permit the flush disposition of wall 26.

The carrier is automatically disposed in the forwardly upwardly inclined open disposition within the housing 12 by means of a pair of shoulders on the housing including an upper shoulder 37 defined by a depending offset portion of top wall 17 as best seen in FIG. 9. The top edge 38 of wall 26 may abut shoulder 37 to limit the rearward inclination of the carrier. Further, the upper edge 39 of the end walls 29 and 30 of the carrier may substantially abut the underside of the housing top wall 17 in the inclined disposition. Bottom wall 14 of housing 12 may be further provided with upstanding shoulders 40 adapted to be engaged by the lower end 41 of edge wall 26 as shown in FIG. 9, to limit the inward movement of the lower edge 41 and thereby automatically dispose the carrier in the inclined open disposition for facilitated handling of the cassettes carried thereby. As best seen in FIGS. 4 and 6, carrier bottom wall 25 is provided with recesses 42 which accommodate the shoulders 40 in the storage disposition of the carrier.

As shown in FIG. 3, housing rear wall 18 may be provided with a pair of slots 43 suitable for use in hanging the holder on a wall support as desired.

As further shown in FIGS. 3 and 4, the rear wall is provided with a pair of openings 44 adjacent the side walls 15 and 16 permitting the user to insert his fingers therethrough to urge the carrier forwardly from the storage disposition against the holding action of the restraining means defined by bosses 33 and openings 34.

The use of holders 10 is extremely simple. The user merely slides the desired cassettes into the carrier compartments 28 to the inserted disposition illustrated in FIG. 1 wherein the cassettes rest on the carrier bottom wall 25 and upright wall 26. In the open disposition of FIG. 1, the cassettes project forwardly from the holder for facilitated use. Further, the carrier is automatically disposed in a forwardly upwardly inclined disposition to further facilitate the manipulation of the cassettes. The carrier is installed in the housing by a simple insertion thereof through front opening 19 of housing 12 until carrier portion 38 abuts shoulder 37 and carrier portion 41 abuts shoulder 40 in the fully inserted arrangement of FIG. 9.

When it is desired to close the holder with the cassettes stored therein, the user merely removes the carrier from the housing by suitable forward urging of the carrier by the user's fingers inserted through the openings 44. Upon separation of the carrier from the housing, the carrier is reversely positioned and reinserted through the housing opening 19 to the position of FIG. 2. The carrier is automatically located in the storage disposition by the abutment of carrier portion 36 with housing shoulder 35, as shown in FIG. 5. To remove the carrier from the storage disposition, the user similarly inserts his fingers through openings 44 to release the carrier from the locking means 33, 44 and urge it forward through housing opening 19.

As the holder may be formed by molding, all of the elements associated with housing 12 may be formed integrally therewith and all the elements associated with carrier 13 may be formed integrally therewith whereby the holder effectively comprises a two-piece structure of effectively maximized simplicity and economy of construction.

The foregoing disclosure of specific embodiments is illustrative of the broad inventive concepts comprehended by the invention.

I claim:

1. A holder for selectively storing and presenting a plurality of cartridges and the like, comprising: a housing having a bottom wall, upstanding end walls, a top wall, and a rear wall, said housing defining a front opening; a carrier having a bottom wall and an upright edge wall cooperatively defining a receiving space, and a plurality of upright dividers dividing said space into a plurality of compartments adapted to receive a cassette; and means on said housing and carrier for disposing the carrier in a forwardly upwardly tilted open disposition within the carrier with said edge wall rearmost thereby to present the cassettes in said compartments for facilitated removal and permit facilitated placement into said compartments and to effectively removably retain the cassettes pocketed therein, said carrier being reversely receivable within said housing with said edge wall forwardmost in a storage disposition thereby to close said front opening with the cartridges stored within said housing, said housing having a forwardly opening recess opening to said front opening disposed to expose a portion of the carrier when the carrier is in said storage position for facilitated manipulation of the carrier relative to the housing.

2. The cartridge holder of claim 1 wherein said carrier portion defines grasping means for manipulating the carrier into and from the housing.

3. The cartridge holder of claim 2 wherein said at least one housing end wall front edge is recessed and said grasping means comprises end means on the carrier exposed through said end wall recess in each of said open and storage dispositions.

4. A holder for selectively storing and presenting a plurality of cartridges and the like, comprising:

a housing having a bottom wall, upstanding end walls, a top wall and a rear wall, said housing defining a front opening;

a carrier having a bottom wall and an upright edge wall cooperatively defining a receiving space, and a plu-

rality of upright dividers dividing said space into a plurality of compartments adapted to receive a cassette; and means on said housing and carrier for disposing the carrier in a forwardly upwardly tilted open disposition within the carrier with said edge wall rearmost thereby to present the cassettes in said compartments for facilitated removal and permit facilitated placement into said compartments and to effectively removably retain the cassettes pocketed therein, said carrier being reversely receivable within said housing with said edge wall forwardmost in a storage disposition thereby to close said front opening with the cartridges stored within said housing, said housing end walls being provided with recesses extending rearwardly from said front opening and said grasping means comprising means on said carrier exposed through said recesses.

5. The cartridge holder of claim 4 wherein said grasping means comprises end wall portions on said carrier.

6. A holder for selectively storing and presenting a plurality of cartridges and the like, comprising:

a housing having a bottom wall, upstanding end walls, a top wall and a rear wall, said housing defining a front opening;

a carrier having a bottom wall and an upright edge wall cooperatively defining a receiving space, and a plurality of upright dividers dividing said space into a plurality of compartments adapted to receive a cassette; and

means on said housing and carrier for disposing the carrier in a forwardly upwardly tilted open disposition within the carrier with said edge wall rearmost thereby to present the cassettes in said compartments for facilitated removal and permit facilitated placement into said compartments and to effectively removably retain the cassettes pocketed therein, said carrier being reversely receivable within said housing with said edge wall forwardmost in a storage disposition thereby to close said front opening with the cartridges stored within said housing, said housing being provided with shoulders at the top rear thereof, and said carrier being provided with abutment means removably engaging said shoulders in said open disposition to retain the carrier in said tilted disposition in the housing.

7. A holder for selectively storing and presenting a plurality of cartridges and the like, comprising:

a housing having a bottom wall, upstanding end walls, a top wall and a rear wall, said housing defining a front opening;

a carrier having a bottom wall and an upright edge wall cooperatively defining a receiving space, and a plurality of upright dividers dividing said space into a plurality of compartments adapted to receive a cassette; and

means on said housing and carrier for disposing the carrier in a forwardly upwardly tilted open disposition within the carrier with said edge wall rearmost thereby to present the cassettes in said compartments for facilitated removal and permit facilitated placement into said compartments and to effectively removably retain the cassettes pocketed therein, said carrier being reversely receivable within said housing with said edge wall forwardmost in a storage disposition thereby to close said front opening with the cartridges stored within said housing, said housing including a first shoulder at the top rear thereof and a second shoulder at the bottom front thereof, and said carrier being provided with abutment means removably engaging said shoulders in said open disposition to retain the carrier in said tilted disposition in the housing.

8. The cartridge holder of claim 4 wherein said housing includes stop means for limiting the movement of said

carrier inwardly through said housing opening to dispose said edge wall flush with said top and bottom front edges when said carrier is in said storage disposition.

9. A holder for selectively storing and presenting a plurality of cartridges and the like, comprising:

a housing having a bottom wall, upstanding end walls, a top wall and a rear wall, said housing defining a front opening;

a carrier having a bottom wall and an upright edge wall cooperatively defining a receiving space, and a plurality of upright dividers dividing said space into a plurality of compartments adapted to receive a cassette; and

means on said housing and carrier for disposing the carrier in a forwardly upwardly tilted open disposition within the carrier with said edge wall rearmost thereby to present the cassettes in said compartments for facilitated removal and permit facilitated placement into said compartments and to effectively removably retain the cassettes pocketed therein, said carrier being reversely receivable within said housing with said edge wall forwardmost in a storage disposition thereby to close said front opening with the cartridges stored within said housing, said housing top wall being forwardly upwardly inclined adjacent said opening.

10. A holder for selectively storing and presenting a plurality of cartridges and the like, comprising:

a housing having a bottom wall, upstanding end walls, a top wall and a rear wall, said housing defining a front opening;

a carrier having a bottom wall and an upright edge wall cooperatively defining a receiving space, and a plurality of upright dividers dividing said space into a plurality of compartments adapted to receive a cassette; and

means on said housing and carrier for disposing the carrier in a forwardly upwardly tilted open disposition, within the carrier with said edge wall rearmost thereby to present the cassettes in said compartments for facilitated removal and permit facilitated placement into said compartments and to effectively removably retain the cassettes pocketed therein, said carrier being reversely receivable within said housing with said edge wall forwardmost in a storage disposition thereby to close said front opening with the cartridges stored within said housing, said carrier bottom wall being provided with a rearwardly opening recess, and said housing bottom wall carrier being provided with a shoulder for limiting the insertion of said carrier into the housing in said open disposition, said shoulder being received in said recess when said carrier is disposed in said storage disposition.

11. A holder for selectively storing and presenting a plurality of cartridges and the like, comprising:

a housing having a bottom wall, upstanding end walls, a top wall, and a rear wall, said housing walls having front edges defining a front opening;

a carrier having a bottom wall and an upright edge wall cooperatively defining a receiving space, and a plurality of upright dividers dividing said space into a plurality of compartments adapted to receive a cassette; and

means on said housing and carrier for disposing the carrier in a forwardly upwardly tilted open disposition within the carrier with said edge wall rearmost thereby to present the cassettes in said compartments for facilitated removal and permit facilitated placement into said compartments and to effectively removably retain the cassettes pocketed therein, said carrier being reversely receivable within said housing with said edge wall forwardmost in a storage disposition substantially flush with the said front edges of the bottom and top housing walls thereby to close said front opening with the cartridges stored within said housing.

12. The cartridge holder of claim 11 wherein said housing is provided with a shoulder at the bottom front thereof, and said carrier is provided with abutment means removably engaging said shoulder in said open disposition to retain the carrier in said tilted disposition in the housing.

13. The cartridge holder of claim 11 wherein said carrier and at least one housing end wall are provided with releasable holding means for preventing inadvertent opening of the holder when the carrier is installed in the housing in the storage disposition.

14. The cartridge holder of claim 11 wherein said compartments have a depth preselected to cause the cartridges to project forwardly outwardly therefrom when the cartridges are received therein.

15. The cartridge holder of claim 11 wherein said carrier includes upright end walls extending upwardly from said bottom wall to substantially the level of the top of said edge wall.

16. The cartridge holder of claim 11 wherein said housing bottom and top walls are provided with interlock

means for releasably locking a second such holder onto the top of a first such holder to provide a stacked arrangement of said first and second holders.
